UNITED STATES PATENT OFFICE.

AMSHEL GUEFT-GRINBERG, OF NEW YORK, N. Y.

BUCCO-LINGUAL DENTAL ATTACHMENT.

Application filed August 28, 1923. Serial No. 659,796.

To all whom it may concern:

Be it known that I, AMSHEL GUEFT-GRINBERG, a citizen of Russia, and a resident of New York, in the county of New York and State of New York, have invented certain new and useful Improvements in Bucco-Lingual Dental Attachments, of which the following is a full, clear, and exact description.

This invention appertains to dental attachments generally, and more particularly to a bucco-lingual attachment for use as a bridging for the installation of artificial teeth in the mouth of a patient.

The principal object of the invention is to provide for an attachment of the character mentioned, and one of an extremely simple, inexpensive and efficient construction and arrangement, such as will, when properly installed, act to rigidly retain an artificial tooth, or teeth, in position within the mouth of a patient, but which will also allow for the removal of the tooth or teeth, when desired or necessary.

Another object of the invention is to provide for a bridgework of the class set forth, and one embodying a novel form of resilient attaching member for effecting the proper installation of a tooth, or teeth, in position within the mouth of the patient, and which, while acting to secure the tooth or teeth against accidental displacement from installed position, readily admits of the removal of the same in an easy and convenient manner.

With the foregoing and other equally important objects in view, the invention resides in the certain new and useful construction and arrangement as will be hereinafter more fully described, set forth in the appended claim, and illustrated in the accompanying drawing:—

Figure 1 is a side elevation of a denture embodying the invention,

Figure 2 is an enlarged fragmentary sectional elevation of the same,

Figure 3 is a plan view, partly in section, of an artificial tooth as it appears in bridged position between adjacent natural teeth,

Figure 4 is a perspective view of the preferred embodiment of the resilient anchor or mortise member of the attaching device,

Figure 5 is a plan view of the blank from which the resilient anchor or member is formed, and,

Figure 6 is a perspective view of the keeper or socket member to be detachably engaged by the resilient anchor or mortise.

Referring to the drawing, the bridging attachment or device, as shown therein, comprises generally a keeper or socket member 10 to be suitably embedded in a filling or the like of a natural tooth of a denture A of a patient's mouth, and an anchor or mortise 11 to be attached at one side of an artificial tooth and detachably engaged with the keeper or socket member 10, when the parts are properly installed in position, two of the attachments or devices being employed in each instance of the bridging of an artificial tooth between adjacent natural teeth, substantially as shown in Figures 1 to 3, inclusive.

The keeper or socket member 10 is preferably of a tubular form, rectangular in cross-section, and open at its outer or upper end, with a slotted opening 12 extending longitudinally of one of its flat side faces and inwardly from its open end to a point immediately adjacent its lower closed end.

The anchor or mortise member 11 is formed to provide a central flange or tenon portion 13 and flange portions 14 and 14' disposed in right angular relation at the opposite sides of one of the longer edges of the flange or tenon 13, with resilient tongue members 15 and 15' arranged to overlie the flange portions 14 and 14' to either side of the said flange or tenon 13.

In its preferred embodiment, the anchor or mortise member 11 is made from a single piece or blank of sheet material, rectangular in plan as shown in Figure 5, which is cut-away inwardly of one of its ends, as at 16, to provide the spaced resilient tongue portions or members 15 and 15'. The portions or members 15 and 15' are to be bent on the lines of fold a—a', on the transverse center of the blank, to positions overlying the corresponding portions or flanges 14 and 14' of the other half portion of the blank, while the tenon 13 is to be formed by first bending the uncut portion of the blank on the line of fold b, on the longitudinal center thereof, and then on the lines of fold c—c' to dispose the flange portions 14 and 14' outwardly therefrom in the desired right angular relation thereto. The resilient tongue portions or members 15 and 15' are normally inclined with respect to the flanges 14 and 14', so as to be compressed toward

the opposed faces of the latter, when the anchor or mortise 11 is inserted downwardly of the keeper or socket 10, and whereby the former is frictionally retained against 5 accidental displacement from engagement with the latter.

In the installation of an artificial tooth within the month of a patient, and between adjacent natural teeth B and C of the denture A, as shown in Figures 1 to 3, the adjacent sides of these natural teeth will be drilled or otherwise opened up to receive in each a suitable filling or inlay D in which is to be embedded a socket member 10 with 10 the slotted opening 12 thereof exposed through the filling or inlay material, the slotted opening 12 of the socket 10 of the natural tooth B being arranged directly opposite to the slotted opening of the socket 20 of the natural tooth C and in alignment therewith. The artificial tooth, or artificial tooth denture 17 is now selected or prepared, and is suitably opened up at its opposite sides to receive the tenon portions 13 of a pair 25 of the anchors or mortises 11, and, with the latter rigidly secured in position, the flange portions 14 and 14' thereof will be inserted downwardly of the respective keeper or socket members 10. During the insertion of 30 the flange portions 14 and 14' into the keepers or sockets 10, the resilient tongues 15 and 15' carried thereby will be placed under compression and will frictionally engage the opposed inner wall portions of the outer flat 35 faces of the keepers or sockets 10 to either side of the slotted openings 12, and thereby act to retain the anchors or mortises 11 securely in position against accidental displacement.

40 It will be obvious that the bridge-work thus provided for will be exceedingly simple and inexpensive to manufacture, and, at the same time, extremely efficient and durable in

use, and easy to install. It will, of course, be understood that the parts of the attachment or device are to be made from a non-corrosive flexible and resilient material, such as are generally employed in the practice of dentistry, and that the resiliency of the tongue portions 15 and 15', of the anchor or mortise member 11, will be maintained to provide for the proper frictional engagement of the latter with the keeper or socket member 10 by keeping the tongues in properly spaced relation to the flange portions 55 14 and 14' of the anchor or mortise 11.

From the foregoing, it will be readily apparent that, while a preferred embodiment of the attachment or device has been described and illustrated herein in specific 60 terms and details of construction and arrangement, various changes in and modifications of the same may be resorted to without departing from the spirit of the invention, or the scope of the claim appended 65 hereto.

Having thus fully described the invention, what is claimed, is:—

As an article of manufacture, a dental anchor comprising a blank of sheet material of rectangular formation and having a cutaway portion at one edge thereof to provide spaced resilient tongue members at one side of the transverse center of the blank, the opposite portion of the blank being bent 70 upon itself on the longitudinal center thereof to provide a denture engaging tenon, the latter portion of the blank being further bent on lines parallel to and equidistantly spaced from the line of fold of the said 75 tenon to provide opposite angularly disposed flanges, said resilient tongue members being bent backwardly upon said flanges and disposed in spaced inclined relation with respect thereto.

AMSHEL GUEFT-GRINBERG.
